REFRIGERATION

Gunnar Grubb, Stockholm, Sweden, assignor, by
mesne assignments, to Servel, Inc., New York,
N. Y., a corporation of Delaware

Application September 17, 1938, Serial No. 230,402
In Germany September 30, 1937

6 Claims. (Cl. 62—5)

This invention relates to refrigeration, and more particularly to an absorption refrigeration system of the kind containing an inert gas or auxiliary agent.

It is an object of the invention to provide an improvement in refrigeration systems of this type whereby a condition in the system is automatically modified or changed at intervals. A condition in the system may be modified or changed in accordance with the invention, for example, by bringing about a change of composition of an agent or a fluid in the system.

This is accomplished by accumulating successive bodies of fluid in liquid phase at a place of accumulation in the system, and automatically dumping each body of liquid from time to time from such place of accumulation. The liquid dispersed from the place of accumulation, as pointed out above, is utilized to bring about a desired action or change in a part of the system.

The liquid accumulated may be refrigerant, for example, and the successive bodies of accumulated liquid may be automatically dumped from time to time into the weak gas portion of the gas circuit to bring about a reduction in the gas circulation and cause rise of evaporator temperature to effect defrosting.

Instead of dumping successive bodies of accumulated refrigerant into the gas circuit to reduce gas circulation, the liquid may be automatically dumped from time to time into the evaporator and collected therein, whereby a greater quantity of refrigerant will be available for the production of cold to take care of an increase in load.

The successive bodies of refrigerant which are accumulated may be utilized in different ways to bring about a change in a condition in the system. For example, the bodies of liquid refrigerant may be dispersed from the place of accumulation to a place of vaporization, and the refrigerant vapors may then be conducted to the evaporator to cause rise of evaporator temperature and thereby effect defrosting. The vapors produced in the manner just described may also be utilized to cause flow of liquid from one part of the system to another part of the system by vapor-lift action.

Any fluid circulating in the system can be accumulated in liquid phase at a place of accumulation. In accordance with the invention successive bodies of accumulated liquid automatically flow at desired intervals of time to renew or force liquid from one part of the system to another part of the system, or bring about a change in a condition or of an agent in the system.

The above and other objects and advantages of the invention will be more fully understood upon reference to the following description and the accompanying drawings forming a part of this specification, and in which:

Fig. 1 illustrates more or less diagrammatically a refrigeration system embodying the invention; and

Fig. 2 is a modification of the invention shown in Fig. 1.

In Fig. 1 the invention is embodied in an absorption refrigeration system of a uniform pressure type containing a pressure equalizing gas or auxiliary agent. A system of this type includes a generator 10, condenser 11, evaporator 12, and an absorber 13 which are interconnected in a manner well-known in the art and which will briefly be described hereinafter. The system contains a solution of refrigerant in absorption liquid, such as ammonia in water, for example, and also an auxiliary agent or inert gas, such as hydrogen.

The generator 10 is heated in any suitable manner, as by a gas burner 14, for example, whereby refrigerant is expelled from solution in generator 10. Refrigerant vapor flows upwardly through conduit 15 and an air-cooled rectifier 16 into first condenser section 11a of air-cooled condenser 11.

Refrigerant liquefied in condenser section 11a flows into a trap formed by pipe 17 and conduit 18. When sufficient liquid accumulates in the liquid trap, liquid flows through conduit 18 into upper evaporator section 12a and thence through conduit 19 into lower evaporator section 12b. Evaporator sections 12a and 12b are disposed in a thermally insulated space 20.

Refrigerant fluid in evaporator section 12b evaporates and diffuses into inert gas which enters through conduit 21, thereby producing a refrigerating effect. The rich gas mixture of refrigerant vapor and inert gas formed in evaporator section 12b flows through a vessel 22 and conduit 23 into an outer passage 24 of a gas heat exchanger 25.

Evaporator section 12a is connected by conduits 26 and 27 to outer passage 24 of the gas heat exchanger. Refrigerant fluid in evaporator section 12a evaporates and diffuses into rich gas which circulates therethrough, thereby producing a refrigerating effect and precooling liquid flowing to evaporator section 12b.

Refrigerant vapor not liquefied in first condenser section 11a flows from the upper end of pipe 17 into a second condenser section 11b. Refrigerant liquefied in condenser section 11b

flows through conduits 28, 29, and 19 into evaporator section 12b.

From the outer passage 24 of gas heat exchanger 25 the rich gas mixture flows through conduit 30 into the lower end of air-cooled absorber 13. Absorber 13 is diagrammatically shown in the form of a looped coil having a plurality of cooling fins fixed thereto.

In absorber 13 the rich gas mixture flows counter-current to downwardly flowing weak absorption liquid which enters through conduit 31. The absorption liquid absorbs refrigerant vapor from the inert gas, and inert gas weak in refrigerant flows from absorber 13 through conduit 32, a plurality of tubes 33 forming an inner passage of the gas heat exchanger, and conduit 21 into the upper part of evaporator section 12b.

Absorption liquid enriched in refrigerant flows from the lower part of absorber 13 into a vessel 34. From vessel 34 enriched absorption liquid flows through conduit 35 and an inner passage of liquid heat exchanger 36 to a coil 37 which is disposed about the lower end of generator flue 38. Liquid is raised by vapor-lift action from coil 37 through tube 39 into the upper part of generator 10. Refrigerant vapor expelled out of solution in generator 10, together with refrigerant vapor entering through tube 39, flows upwardly through conduit 15 into condenser section 11a, as explained above.

Absorption liquid from which refrigerant has been expelled flows from generator 10 through conduit 40, outer passage of liquid heat exchanger 36, and conduit 31 into the upper part of absorber 13. This circulation of absorption liquid is effected by raising of liquid in tube 39 by vapor-lift action.

The lower end of condenser section 11b is connected by conduit 28, vessel 41, and conduit 42 to the gas circuit, as at gas heat exchanger 25, for example, so that any inert gas which may pass through the condenser can flow into the gas circuit. Refrigerant vapor not liquefied in condenser 11 flows through conduit 28 to displace inert gas in vessel 41 and force such gas through conduit 42 into the gas circuit. By forcing gas into the gas circuit in this manner, the total pressure in the system is raised whereby an adequate condensing pressure is obtained to insure condensation of refrigerant vapor in 50 the condenser.

Since rich gas flows through evaporator section 12a while gas weak in refrigerant enters evaporator section 12b through conduit 21, the gas in evaporator section 12a contains a greater amount of refrigerant vapor than the gas in evaporator section 12b. The partial pressure of refrigerant vapor is therefore higher in evaporator section 12a than in evaporator section 12b, and evaporation of liquid takes place at a higher temperature in evaporator section 12a than in evaporator section 12b.

Evaporator section 12a may be primarily employed for cooling space 20 and is preferably provided with a relatively extensive heat transfer surface. Evaporator section 12b is preferably provided with a limited heat transfer surface and may be employed as a freezing unit since evaporation of liquid takes place at a lower temperature therein.

During normal operation of the system, refrigerant fluid, inert gas, and absorption liquid circulate in the manner described above, whereby evaporator sections 12a and 12b produce a refrigerating effect. Inert gas or hydrogen cir-

culates continuously in the gas circuit including evaporator 12 and absorber 13. This circulation of inert gas is due to the difference in specific weight of the rich gas mixture in evaporator section 12b, outer passage 24 of gas heat exchanger 25, and conduit 30; and the weak gas mixture in absorber 13, conduit 32, inner passage 33 of the gas heat exchanger, and conduit 21.

10 Since the rich gas is heavier than the weak gas, a force is produced or developed in the gas circuit for causing flow of rich gas toward absorber 13 and flow of weak gas toward evaporator section 12b. Likewise, due to the difference in specific weight of rich gas in conduit 26 and richer gas in evaporator section 12a and conduit 21, a force is developed for causing flow of gas in the local circuit including evaporator section 12a.

15 In accordance with this invention successive bodies of fluid in liquid phase are accumulated at a place of accumulation and automatically dumped intermittently from such place of accumulation. The successive bodies of liquid automatically dumped intermittently from the place of accumulation are utilized to bring about a change of composition of an agent or fluid in the refrigeration system. Stated another way, bodies of liquid are accumulated and withdrawn 20 from circulation at one place in the system and automatically introduced at intervals of time in another portion of the system to modify or change a condition in the system.

25 In the particular embodiment of the invention shown in Fig. 1 refrigerant fluid in liquid phase is accumulated at a place of accumulation, and successive bodies of accumulated refrigerant are automatically dumped at intervals of time into the weak gas column of the gas circuit to change the composition of the weak gas and bring about a reduction in the refrigerating effect produced by evaporator section 12b.

30 This may be accomplished by connecting a vertically extending conduit 43 to an upper part 45 of condenser section 11a at 44. The conduit 43 is formed with a U-shaped portion to provide a liquid trap or place of accumulation 45. Liquid flows from trap 45 at the overflow 46. The internal diameter of conduit 43 is sufficiently small so that liquid and gas cannot freely pass each other therein.

35 The lower end of conduit 43 is connected at 47 to a larger conduit or pipe section 48 having an internal diameter sufficiently large whereby 50 gas and liquid can freely pass each other. The lower end of pipe section 48 is connected at 49 to conduit 32 through which gas weak in refrigerant normally flows from absorber 13 to evaporator section 12b.

60 In operation, vapors flowing through conduit 15 from generator 10 first flow into air-cooled rectifier 16 in which absorption liquid for the most part is condensed and returned through conduit 15 to generator 10. Refrigerant vapor 65 begins to condense and liquefy in the upper part of condenser section 11a. Liquid refrigerant formed in the extreme upper part of condenser section 11a and ahead of connection 44 of liquid trap 45 can flow into the latter and accumulate 70 therein.

75 The interval of time required to fill trap 45 with liquid will depend upon the rate at which heat is supplied to generator 10, the extent of cooling effected in the portion of condenser section 11a between rectifier 16 and connection 44

of liquid trap 45, and the size of the liquid trap. The size of liquid trap 45 and the point where it is connected to condenser section 11a can be selected so that, even when heat is supplied to generator 10 at a maximum rate, it will take a desired interval of time for liquid to fill trap 45 to the overflow 46. This interval of time may be chosen so that it will take several hours or days for liquid to accumulate in trap 45 to the overflow 46.

When sufficient liquid accumulates in trap 45 to reach overflow 46, liquid will automatically flow by siphon action from the trap through conduit 43 into pipe section 48. Flow of liquid by siphon action is effected inasmuch as the internal diameter of trap 45 and conduit 43 is sufficiently small so that liquid and gas cannot freely pass each other therein. When the liquid column in the left-hand leg of trap 45 becomes sufficiently high to start siphoning past overflow 46, the liquid column flows uninterruptedly from the liquid trap. In effect the body of accumulated liquid is automatically dumped into pipe section 48 when a predetermined amount of liquid has accumulated in trap 45. When liquid reaches the connection 47 the liquid column is broken up and the liquid flows downwardly along the walls of pipe section 48 and thence into conduit 32.

The liquid flowing into conduit 32 from pipe section 48 evaporates and diffuses into weak gas flowing from absorber 13 to evaporator section 12b. This increases the specific weight of the column of weak gas in the gas circuit and reduces the difference in specific weight of the columns of rich and weak gas, whereby the force normally developed for circulation of gas in the gas circuit is reduced. At the termination of a liquid dumping period from trap 45 and before sufficient liquid has again accumulated in the trap to seal the latter, condenser section 11a is in open communication with the gas circuit. In addition to liquid refrigerant evaporating and diffusing into weak gas, therefore, relatively warm refrigerant vapor can also flow from condenser section 11a into conduit 32.

During the period when gas circulation is reduced, less cold is produced by evaporator section 12b and the temperature of the evaporator section rises. By properly selecting the size of trap 45 and dumping sufficient liquid into the gas circuit, the temperature of evaporator section 12b can be caused to rise sufficiently high so that frost formed thereon will melt. With the arrangement provided defrosting can be effected very rapidly.

When the trap 45 is again sealed by liquid refrigerant accumulating therein, condenser section 11a is no longer in communication with the gas circuit. Normal circulation of gas will be resumed in the gas circuit and a refrigerating effect will be produced by the evaporator. When sufficient liquid has accumulated in trap 45 to reach overflow 46, another body of accumulated liquid will be dumped into conduit 32. Thus successive bodies of liquid are accumulated in trap 45 and each body of liquid is automatically dumped after an interval of time to modify or change a condition in the refrigeration system. When liquid refrigerant is dumped in the weak gas column, the composition of the weak gas is changed to bring about a reduction in gas circulation in the gas circuit.

The heating of generator 10 may continue during the periods when circulation of gas in the gas circuit is reduced or completely stopped and li-

uid refrigerant may therefore continue to flow from condenser 11 into evaporator 12. To prevent unevaporated refrigerant from flowing out of the lower part of evaporator section 12b when circulation of gas in the gas circuit is reduced, vessel 22 is connected to the lower part of evaporator section 12b to collect unevaporated refrigerant. In addition to providing vessel 22 the coil forming evaporator section 12b may be provided with inserts 50 so that shallow pools of liquid can form therein.

The vessel 22 is provided with spaced baffles 51 having upper openings 52 and other spaced baffles 53 having lower openings 54. Further, the left-hand end of vessel 22 is provided with an overflow conduit 55 connecting the lower part of the vessel and conduit 23 at approximately the height of upper openings 52. The baffles 51 and 53 and conduit 55 are provided so that vessel 22 can be purged of absorption solution. In the larger pockets liquid refrigerant presses down absorption solution whereby the latter flows through openings 54. In the alternate small pockets absorption solution is raised by mechanical lifting effected by liquid. The vessel 22 can therefore be purged of absorption solution which flows therefrom through conduit 55.

When normal gas circulation in the gas circuit is resumed after liquid has been dumped from trap 45, liquid refrigerant in vessel 22 is immediately available to produce a refrigerating effect. This is particularly advantageous when the load or evaporator section 12b is increased, as by the insertion of trays containing water to be frozen. Under such conditions more liquid refrigerant can evaporate and diffuse into inert gas and the accumulated liquid in vessel 22 is immediately available in the freezing unit to take care of the temporary increase in load.

In Fig. 2 is illustrated a modification of the invention in which parts similar to those shown in Fig. 1 are designated by the same reference numerals. Fig. 2 differs from Fig. 1 in that the lower end of pipe 17 is connected to a conduit 56 having a horizontal portion and an upwardly extending vertical portion. The pipe 17 and conduit 56 form a U-shaped liquid trap in which liquid refrigerant from condenser section 11a accumulates before it flows through conduit 18 into evaporator section 12a. The lower vertical portion of conduit 56 is arranged in heat exchange relation with conduit 15 by means of a metal member 57.

The upper end of conduit 56 is connected to an end of a downwardly inclined or slanting conduit 58 to which the cooling fins 59 of condenser 11 are fixed. The lower end of conduit 58 is bent upwardly to provide a liquid trap 60. The upwardly bent portion is then bent downwardly to form an overflow 61. From overflow 61 liquid can flow downwardly in conduit 62 which is connected at 63 to a pipe section 64. The pipe section 64 is connected at 65 to conduit 32 through which weak gas normally flows from absorber 13 to evaporator section 12b.

In operation, liquid in the vertical portion of conduit 56 is slowly vaporized by heated metal member 57 which in turn is heated by the relatively warm vapors flowing through conduit 15 from generator 10. The vapor in conduit 56 flows upwardly into conduit 58 where it is liquefied and condensed. The liquid accumulates in trap 60, and, when liquid reaches overflow 61, the liquid in the trap is automatically dumped by siphon action into conduit 64 and thence

into conduit 32. As in the embodiment of Fig. 1, the liquid changes a condition in the system by evaporating and diffusing into weak gas to bring about a reduction in gas circulation, whereby the temperature of the evaporator is increased to cause defrosting.

The rate at which liquid vaporizes in the vertical portion of conduit 56 can be readily controlled and made very slow, whereby the length of time it takes liquid trap 60 to fill with liquid can be made of any duration. The member 57 may be formed of metal or other suitable material may be employed having less heat conductivity. The conduit 56 and member 57 may be spaced apart and the air gap therebetween bridged with different metal members permitting more or less heat to be transmitted to conduit 56. The internal diameter of liquid trap 60 and conduit 62 is sufficiently small whereby liquid and gas cannot freely pass each other therein. On the other hand, pipe section 64 may be of larger diameter so that liquid and gas can freely pass each other.

Although several embodiments of the invention have been shown and described, it will be apparent to those skilled in the art that various modifications and changes may be made without departing from the spirit and scope of the invention. In Fig. 1, for example, liquid trap 45 may be connected to a separate small auxiliary condenser adapted to receive vapors expelled from solution in generator 10. It is therefore contemplated to cover all modifications and changes which come within the true spirit of the invention, as pointed out in the following claims.

What is claimed is:

1. In the art of refrigeration in which evaporation of liquid refrigerant takes place in the presence of an inert gas in a place of evaporation to produce a refrigerating effect, inert gas enriched with refrigerant vapor flows from the place of evaporation to a place of absorption, and inert gas weak in refrigerant vapor flows from the place of absorption to the place of evaporation, the flow of gas being due to the difference in specific weight of the enriched and weak gas columns, the improvement which consists in collecting refrigerant fluid in liquid phase at a place of accumulation, and intermittently flowing accumulated liquid into the weak gas column when a predetermined quantity of liquid has collected in the place of accumulation, whereby the flow of gas between the place of evaporation and place of absorption is reduced to lessen said refrigerating effect.

2. In the art of refrigeration with a system in which vaporous refrigerant flows to a place of condensation and condensed refrigerant flows from the latter to a place of evaporation, the improvement which consists in accumulating refrigerant fluid in liquid phase in a place of

accumulation to provide a liquid seal in a path connecting the place of evaporation and said path of flow of vaporous refrigerant, and opening the seal by intermittently dumping liquid from the place of accumulation responsive to liquid level.

3. In the art of refrigeration in which flow of auxiliary agent takes place in a circuit having a place in which refrigerant evaporates in the presence of the agent to produce a refrigerating effect, the improvement which consists in collecting liquid in a place of accumulation, intermittently dumping liquid from the place of accumulation when a predetermined quantity of liquid has collected therein, and utilizing the dumped liquid to disturb the flow of auxiliary agent in said circuit to lessen said refrigerating effect.

4. In the art of refrigeration in which flow of auxiliary agent takes place in a circuit having a place in which liquid refrigerant evaporates in the presence of the agent to produce a refrigerating effect, the improvement which consists in collecting liquid refrigerant in a place of accumulation, intermittently dumping liquid into said circuit from the place of accumulation when a predetermined quantity of liquid refrigerant has collected in the latter, and utilizing the liquid dumped into said circuit to disturb the flow of auxiliary agent therein to lessen said refrigerating effect.

5. An absorption refrigeration system of an inert gas type comprising interconnected parts including a gas circuit having a cooling element into which liquid refrigerant is conducted for evaporation in the presence of inert gas to produce a refrigerating effect, means providing a place for accumulating liquid, and said last-mentioned means being embodied in the system in such a manner and being so constructed and arranged that it is self-acting to cause intermittent removal of liquid therefrom to another part of the system to disturb the flow of inert gas in said gas circuit to reduce said refrigerating effect.

6. An absorption refrigerating system of an inert gas type comprising interconnected parts including a gas circuit having a cooling element into which liquid refrigerant is conducted for evaporation in the presence of the inert gas to produce a refrigerating effect, means providing a place for collecting liquid refrigerant and a connection therefrom to said gas circuit, and said last-mentioned means being embodied in the system in such a manner and being so constructed and arranged that it is self-acting to cause liquid refrigerant to flow intermittently therefrom through said connection to disturb the flow of inert gas in said gas circuit to reduce said refrigerating effect.

GUNNAR GRUBB.
